US0D1064662S

(12) United States Design Patent (10) Patent No.: US D1,064,662 S
(45) Date of Patent: * Mar. 4, 2025

(54) SITTING CUSHION HAVING A CUTOUT PORTION

(71) Applicant: Linda Moffett, Spearfish, SD (US)

(72) Inventor: Linda Moffett, Spearfish, SD (US)

() Term: 15 Years

(21) Appl. No.: 29/835,104

(22) Filed: Apr. 15, 2022

Related U.S. Application Data

(62) Division of application No. 29/753,763, filed on Oct. 1, 2020, now Pat. No. Des. 948,894, which is a division of application No. 29/702,201, filed on Aug. 16, 2019, now Pat. No. Des. 897,734, which is a division of application No. 29/594,433, filed on Feb. 17, 2017, now Pat. No. Des. 856,706.
